UNITED STATES PATENT OFFICE.

BLAINE A. STAIR, OF LOS ANGELES, CALIFORNIA.

SEWING-THIMBLE.

No. 866,582.

Specification of Letters Patent.

Patented Sept. 17, 1907.

Application filed September 13, 1906. Serial No. 334,542.

To all whom it may concern:

Be it known that I, BLAINE ARTHUR STAIR, of the city of Los Angeles, in the county of Los Angeles and State of California, have invented an Improvement in Sewing-Thimbles, of which the following is a full, clear, and exact description or specification, reference being had to the annexed drawings and to the letters and figures marked thereon.

My invention relates to a certain new and useful improvement in sewing thimbles.

Upon the annexed sheet of drawings Figure 1, is a front elevation of a thimble on an exaggerated scale, constructed according to my said invention, showing a cutter at the upper part of the thimble. Fig. 2, is another elevation of the said thimble at right angles to Fig. 1. Fig. 3, is a front elevation of my new or improved thimble with the thread cutting device as applied to the lower part thereof. Fig. 4, is another elevation of Fig. 3, showing the cutter at right angles to the position 20 of the cutter in Fig. 3. Fig. 5, is a front elevation of the thimble with my invention applied thereto as a double cutter. Fig. 6, is another elevation corresponding to Fig. 5, and at right angles to Fig. 5.

In Figs. 1, and 2, the cutter A, constructed in combination with the thimble is shown at the upper part of the thimble. The cutter A, is fastened to the upper part of a bur punched outwardly from the interior to the exterior of the metal of the thimble by a manually operated punch, so that the metal forming the bur 25 round about the outer part of the hole C, punched in the metal of the thimble, projects sufficiently far outwards on the exterior thereof, to enable a corresponding and preferably square hole C, in the lower part of the cutter A, to be passed over the bur, after which the bur 30 is flattened over the upper part of and around the square hole C, in the cutter A. The cutter A, is formed as shown at Figs. 1, and 2, of thin steel, bronze or equivalent metal which will maintain a sufficiently sharp edge so that it will cut thread when the thread is drawn 35 against it as shown at Figs. 1, and 2. The two cutting edges are marked D, and E, respectively, and the upper part of the cutter is bent outwards as shown espe-

cially at Fig. 2, to enable the thread to be easily caught by the hand of the operator upon the outwardly turned top of the cutter, and then drawn down upon either of 45 the cutting edges D, or E. Although the space between the cutter A, and the thimble F, is shown of exaggerated width in Fig. 2, it is to be understood that this exaggerated width is indicated upon the drawing for the purpose of showing that the upper part of the 50 cutter A, is not fastened to the body of the thimble, but it constitutes a spring, which when the thread G, is drawn into or upon the cutter, allows the thread G, to easily pass down through the yielding spring in the upper part of the cutter A.

In Figs. 3, and 4, the cutter A, is of precisely the same construction as that hereinbefore described with reference to Figs. 1, and 2, and the operation thereof is also the same as that hereinbefore described with reference to Figs. 1, and 2, therefore it is unnecessary to 60 further describe Figs. 3, and 4, excepting to point out that the cutter A, is placed at the lower part of the thimble instead of at the upper part thereof.

The cutter shown in Figs. 5, and 6, differs only from the cutter shown at Figs. 1, 2, 3, and 4, in respect that 65 the cutter is of duplex construction, and consists of the upper and lower cutter respectively marked A, and A', and fastened to the thimble about the central part thereof by the bur around the square hole C, which bur 70 being flattened by a pincer punch or otherwise flattened, holds the cutter firmly and conveniently in about a midway position on the side of the thimble.

I claim as my invention.

The thimble, combined with which is a double edged spring cutter, said spring cutter being fastened to the 75 thimble by means of a bur engaging with a hole in the spring cutter, the bur having its outer end flattened for fastening the cutter to the thimble, substantially as hereinbefore described.

In testimony whereof, I have hereunto set my hand and 80 seal at the city of Los Angeles aforesaid, in the presence of two subscribing witnesses.
